UNITED STATES PATENT OFFICE

141,522

DESIGN FOR A BALL-CAGE TOY

David Davidson, Los Angeles, Calif.

Application February 22, 1945, Serial No. 118,085

Term of patent 3½ years

(Cl. D34—15)

To all whom it may concern:

Be it known that I, David Davidson, a citizen of the United States, residing at Los Angeles, in the county of Los Angeles and State of California, have invented a new, original, and ornamental Design for a Ball-Cage Toy, of which the following is a specification, reference being had to the accompanying drawing, forming a part thereof.

The figure in the drawing is a front perspective view of a ball-cage toy, showing my new design.

I claim:

The ornamental design for a ball-cage toy, as shown.

DAVID DAVIDSON.
